PRINTING DEVICE FOR PRINTING MACHINES

Harmon P. Elliott, Watertown, Mass.

Application April 6, 1932, Serial No. 603,562

6 Claims. (Cl. 101—369)

This invention relates to printing plates for printing or addressing machines.

Certain printing, and particularly addressing, machines have the type characters, or addresses, carried by a series of metal plates which are moved in succession through the printing position of the machine.

It is frequently desirable to use, at times, only certain ones and at other times certain others of the entire collection of printing plates for printing. It is impractical to remove selected plates from the collection for printing and then to restore them in their original order to the collection. Hence it is common practice to run the entire collection through the printing machine and to employ selector mechanism which is operated in accordance with certain characteristics of the plates to control the printing operation, those from which a printing operation is to be effected causing the operation of the printing mechanism and the unwanted plates passing through the machine without causing the printing mechanism to operate.

The selector mechanism, which controls the operation of the printing mechanism in the type of machine in which the printing devices of the present invention are used, is electrically controlled. Means is provided by which the successive printing devices are felt by an electric contact member that reciprocates into and out of the line of movement of each printing device. If the printing device permits said contact member to engage a cooperating contact member and thereby to complete an electric circuit, the closing of the circuit effects the control of the selector mechanism to effect a printing operation on that printing device. The arrangement can be reversed, also, and a printing operation caused to be made on that device that does not permit the circuit to be completed.

The printing device with which the present invention is particularly concerned comprises a metal printing plate. Since the plate is electrically conducting it can not be used directly to control the engaging of the selector contact members and hence the metal plate ordinarily has provision for removably receiving one or more metal tabs which project from an edge of the plate and can be positioned at any of a plurality of predetermined positions along the edge of the plate, the tabs being arranged to control the engaging of the selector contact members. Due, however, to the fact that the tabs of necessity must have substantial dimensions and the plates must have recesses, shoulders or the

like for defining the locations for the tabs, and for holding them in place, the number of tabs is strictly limited. There is need for a metal printing plate having a greater number of selector devices than can be accommodated by the usual construction of metal printing plate. For instance, a manufacturing concern may sell one hundred different products and it may desire to circularize those only of all its customers who buy but one special product. Hence it is desirable to have a printing device that can have as many selector positions as there are products. A metal printing device having provision for a relatively great number of selector positions constitutes an object of the present invention.

In carrying out my present invention, I utilize the metal printing plate as one of the selector contact members and place over the face of the plate, preferably on the side opposite the printing characters, an electrically insulating cover, preferably of paper which, also preferably, is removably connected to the plate so that when removed it can be restored to the same position thereon. The insulating cover has provision for receiving a large number of selector perforations therethrough, around the printing characters and, usually, on all four sides thereof. The reciprocable selector contact member is adapted to pass through a perforation and engage the metal plate and thereby effect the operation of the printing mechanism, if the perforation and the contact member are in registration. If a perforation is not in register with the contact member, the insulating cover prevents the contact between the contact member and the plate, so that the plate is caused to pass through the printing mechanism while the latter is held idle. Such an arrangement constitutes a further object of the invention.

A further object is generally to improve the construction of printing devices for printing machines.

Fig. 1 is a plan view of one form of metal printing plate embodying the present invention.

Fig. 2 is a section taken along line 2—2 of Fig. 1.

Fig. 3 is a perspective view of the plate of Fig. 1, with a part of the insulating selector cover broken away.

Fig. 4 is a more or less diagrammatic view illustrating the manner of using the plate.

Fig. 5 is a plan view of a printing plate having a modified form of selector cover or sheet.

Fig. 6 is a detail of a corner of a printing plate

wherein an abutment is provided to define the position of the selector cover on the plate.

The metal printing plate herein illustrated in connection with the present invention comprises 5 a generally fiat rectangular body 10 having its opposite long marginal portions folded over against the back face of the body portion as indicated at 12. The opposite short sides also have folded-over portions or lips 14 which over- 10 lie the marginal portions 12. The lips 14 are provided with parallel raised ribs 16 as is common with this type of plate. The printing characters 18 are embossed in the back face of the plate and stand out in relief on the opposite 15 or front face of the plate.

In accordance with the present invention the printing plate is provided with an electrically-insulating selector cover 20 which, as here shown, comprises a paper card that overlies the rear 20 face of the plate and, for the maximum number of selector positions, covers as much of the address-free portion of the plate as is practicable. The cover card can be secured to the plate in any suitable manner. As here shown 25 the card is as wide as the plate and the short edges thereof are located between the body of the plate and the lips 14 and are held by the frictional engagement of said lips against unintentional displacement. The card is accurately 30 positioned on the plate by aligning one of its edges with a corresponding edge of the plate. If desired, however, some positive abutments can be provided against which the card can be positioned. The lips 14, for instance, at their similar 35 ends can be provided with downwardly reflexed ends 22, see Fig. 6, against which one long edge of the selector card can be positioned. Other positioning means, not necessarily shown, for the card can be provided. The card can bear 40 on its exposed face a facsimile 24 of the printing characters 18 of the plate, as illustrated in Figs. 1 and 2, so that the address borne by the plate can be determined readily or the card can have an opening 26, as illustrated in Fig. 5, 45 through which the embossed printing characters of the plate are exposed, so that said characters can be read directly.

All of the surface of the card, except preferably the space occupied by the facsimile 24, or 50 overlying the printing characters 18, is available for the location of selector perforations 28. It will be understood that the card need not have, necessarily, as many perforations 28 as there are locations therefor, but that a perforation may 55 be in one location in the card of one printing plate and in another location in the card of another printing plate. In the example previously given, where a concern sells a hundred different items and has customers for the separate items, 60 the cards of the printing plates should have provision for one hundred different perforation-locations, yet each card may have but one perforation, all being in different locations on the cards, each located to accord with the particular item 65 for which the address borne by the printing plate associated with the card is a customer. Since, however, a customer usually purchases more than one of the products of a concern, the card associated with the customer's address will have a 70 number of perforations, located to accord with the kinds of goods purchased by the customer. It will be understood that this example is only one of the many different uses that can be made of printing devices having selector perforations 75 or the like.

The cards herein illustrated are provided with a large number of selector perforations 28, which perforations are shown mainly to illustrate the locations for such perforations. The usual card will not need a perforation at every location for one. The perforation-locations can occupy the entire face of the card, spaced as close as is practicable and desirable. The perforations can extend in single or multiple rows parallel with all four edges of the card around the space which overlies the printing characters of the plate, although the idea of having perforations in the card directly above the printing characters is not herein precluded. The perforations will be located in the card in accordance with a pre-conceived plan so that a perforation in the same corresponding location in a plurality of cards means the same thing. 80 85 90

In this manner, the metal printing plate can be provided with a much larger number of selector devices than heretofore. 95

The use of the invention is illustrated in Fig. 4. The printing device is moved in a step by step manner along a guide way 30 toward the printing mechanism, not shown, and is in electrical contact therewith. At some time when the device is stationary it is located under a reciprocating selector arm 32 which has provision for receiving a sufficient number of metal selector pins 34, one of which is here shown, which can 100 be located in accordance with the pattern of the perforation-locations in the insulating card of the printing device. The arm is reciprocated into and out of engagement with the stationary printing device. If a pin 34 comes in contact with the 110 card at a location where there is no selector perforation, the insulating card prevents the pin from making electrical contact with the metal printing plate. Hence no circuit is completed and the printing machine is caused to pass the printing plate through the printing mechanism without making a printing operation on it. If, however, the selector pin finds a perforation under it, and goes into the perforation and makes electrical contact with the plate, the selector-control 120 circuit is completed and the printing plate is operated on by the printing mechanism. 115 125 130

The selector card 20 preferably is removable from the printing plate so that selector perforations can be added thereto when desired. The 125 card illustrated in Fig. 3 is adapted to have the address 24 printed thereon by its printing plate and then secured in position on the plate. If it is not intended to add selector perforations to the card after it is first applied to the plate, the card 130 can be more or less permanently attached to the plate.

The structural character of the selector card is not herein of importance except that it is intended to be electrically insulating. The card or 135 plate cover can be composed of paper or other electrically insulating material. Instead of being mechanically secured to the plate, the card or cover can be adherently secured thereto.

The particular design of the printing plate is 140 not herein of importance except that it has a metal surface or surfaces under the selector perforations, which surfaces can be in electrical contact with a guideway or a circuit terminal of the selector control circuit at the time the plates are 145 felt by the selector mechanism.

I claim:

1. A printing device for a printing machine comprising a metal plate having impressed printing characters on one face and an electrically 150

- insulating cover that overlies at least a part of the other face of the plate, said cover having means by which a contact member can make electrical connection therethrough with said plate.
- 5 2. A printing device for a printing machine comprising a metal plate having impressed printing characters on the front face thereof and an electrically insulating cover for at least a part of the rear face thereof, said cover overlying the 10 rear face of said metal plate entirely about the region of said printing characters and in such overlying portion having at least one selector-opening therein through which electrical contact with said metal plate can be made.
- 15 3. A printing device as defined in claim 2 wherein said cover also has means which give information as to the nature of the printing characters of said metal plate.
4. A printing device for printing machines comprising a metal plate having printing characters which are embossed in the rear face of said plate and are in relief on the front face thereof, and an electrically insulating cover for the rear face and the embossed printing characters having one or 25 more selector-openings therein which expose the plate thereunder and through which openings electrical contact can be made with said plate,
- 80 5. A printing device for printing machines comprising a metal plate having printing characters which are embossed in the rear face of said plate and are in relief on the front face thereof, and an electrically insulating cover plate for the rear face having one or more selector-openings therein which expose the metal plate thereunder and through which openings electrical contact can be made with said plate, said insulating plate having an opening which entirely bounds and exposes to view at least certain of the printing characters of said metal plate.
- 85 6. A selector card for the metal printing plates of printing machines comprising an electrically insulating sheet which is adapted to overlie a portion of the metal plate and has a selector-perforation therethrough by which electrical contact can be established with said plate wherein the card has an opening which entirely bounds and exposes the printing characters of the printing plate, the selector-perforation being located in the card outside of said opening.
